[57] ABSTRACT

This invention relates to novel compounds, methods for preparing them and pharmaceutical compositions containing them, and a process for the prophylactic treatment of allergic conditions employing said compositions. These novel compounds are embraced by

the formula

wherein R is selected from the group consisting of hydrogen, lower alkyl of 1 through 3 carbon atoms, phenyl, an alkali metal, aluminum, calcium, magnesium, or an amine cation, said amine being selected from the group consisting of ammonia, an alkyl amine, ethanolamine, tris-(hydroxymethyl)aminomethane, D-threo-2-amino-1-(p-nitrophenyl)-1,3-propanediol, N,N-bis(hydroxyethyl)piperazine, 2-amino-2-methyl-1-propanol, 2-amino-2-methyl-1,3-propanediol and 2,2-bis(hydroxymethyl)-2,2',2"-nitrolotriethanol; Z is selected from the group consisting of hydrogen, phenyl, and lower alkyl of 1 through 3 carbon atoms; A is selected from the group consisting of

wherein R¹ and R² are selected from the group consisting of hydrogen and lower alkyl of 1 through 6 carbon atoms.

The compounds (I), above, are formulated with pharmaceutical carriers for oral, parenteral, rectal and local administration with insufflation being the preferred method. The compositions are useful in the prophylactic treatment of sensitized humans and mammals for allergy and all anaphylactic reactions of a reagin or non-reagin mediated nature.

DERIVATIVES**

BRIEF SUMMARY OF THE INVENTION

This invention relates to novel compounds, methods for preparing them and pharmaceutical compositions containing them, and a process for the prophylactic treatment of allergic conditions employing said compositions.

In accordance with this invention the compounds of Formula I, above, are represented by the structural formulae *Ia* and *Ib*, below, which are its tautomeric forms. It is to be understood that the compounds of this invention are likely to be mixtures of all tautomeric forms, the percentages of each tautomer being dependent on the nature of R and Z and the physical environment of the compound.

For the purpose of brevity throughout the specification and appended claims, the compounds of Formula I will be referred to hereafter in their keto form of structural formula *Ia*, above.

In structural Formulae *Ia* and *Ib*, above, R is selected from the group consisting of hydrogens, lower alkyl of 1 through 3 carbon atoms, phenyl, an alkali metal, aluminum, calcium, magnesium, or an amine cation, said amine being selected from the group consisting of ammonia, an alkyl amine, ethanolamine, tris-(hydroxymethyl)-aminomethane, D-threo-2-amino-1-(p-nitrophenyl)-1,3-propanediol, N,N-bis(hydroxyethyl)piperazine, 2-amino-2-methyl-1-propanol, 2-amino-2-methyl-1,3-propanediol and 2,2-bis(hydroxymethyl)-2,2',2"-nitrilotriethanol; Z is selected from the group consisting of hydrogen, phenyl, and lower alkyl of 1 through 3 carbon atoms; A is selected from the group consisting of

wherein R¹ and R² are selected from the group consisting of hydrogen and lower alkyl of 1 through 6 carbon atoms.

The terms employed throughout this specification have the meaning ordinarily understood in the chemical art. Examples of alkali metals include lithium, sodium and potassium. Examples of lower alkyl of from 1 through 3 carbon atoms include methyl, ethyl, propyl and isopropyl. Examples of lower alkyl of 4 through 6 carbon atoms include butyl, pentyl and hexyl and the isomeric forms thereof. Examples of alkyl amine include monoethylamine, monomethylamine, mono-propylamine, mono-isopropylamine, diethylamine, di-methylamine, dipropylamine, diisopropylamine, triethylamine, trimethylamine, tripropylamine and triisopropylamine. Examples of amine cation include all

pharmacologically acceptable amine cations, for example, the cations from ammonia, methylammonia, diethylammonia, triethylammonia, dimethylammonia, di-propylammonia, triisopropylammonia, tris-(hydroxymethyl)-aminomethane, D-threo-2-amino-1-(p-nitrophenyl)-1,3-propanediol, N,N-bis(hydroxyethyl)piperazine, 2-amino-2-methyl-1-propanol, 2-amino-2-methyl-1,3-propanediol and 2,2-bis(hydroxymethyl)-2,2',2"-nitrilotriethanol. Pharmaceutically acceptable salts can be prepared from the free acids of compounds of Formula I, or from other salts, e.g., by metathesis or transesterification, in accordance with procedures known in the art. I.

The novel compounds of Formula I of this invention and intermediates therefor are prepared in accordance with the procedures of Processes A and B described below.

PROCESS A

20 The compounds of the formula

wherein A has the same meaning as above and R has the same meaning as above except hydrogen, are prepared by the steps comprising

1. mixing a corresponding compound of the formula

IV

35 wherein Q is lower alkyl of 1 through 3 carbon atoms or phenyl with a corresponding compound of the formula

wherein A has the same meaning as above, to yield a corresponding compound of the formula

50 wherein A and Q have the same meaning as above;

2. heating a thus produced corresponding compound resulting from step (1) to yield a corresponding compound of Formula I, above.

55 A third step is required for preparing the compounds of the formula

60 wherein A has the same meaning as above, namely, hydrolyzing a corresponding compound produced in the manner described in step (2) immediately above and having the formula

wherein A and Q have the same meaning as above, e.g., with an alkali metal hydroxide and then adding thereto a strong acid.

1. The first step of Process A comprises mixing a dialkylacetylene dicarboxylate (IV) with a compound of Formula III, e.g., a 2,7-diaminofluorene, in a molar ratio of approximately 2 of the former (IV) to 1 of the latter (III) reactants, to yield a corresponding diadduct, a tetraalkyl 2,2'-[(fluorene-2,7-diyl)diimino]butenedioate (II). Molar ratios in excess of 2:1 (e.g., 3:1 to 5:1) are also satisfactory. Appropriate solvents for the reaction are alkanols of from 1 through 6 carbon atoms, preferably of from 1 through 3 carbon atoms, benzene, diethylether, dioxane, tetrahydrofuran, or any other solvent which puts both reactants (IV and III) into solution and allows formation of the desired compound (II). Generally the reaction proceeds readily at room temperature and can be accelerated by increasing the temperature to about 100°C.

2. In this step, ring closure of a diadduct (II) produced in step (1) and formation of the desired corresponding dialkyl 1,4,7,10-tetrahydro-4,7-dioxo-12H-cyclopenta[2,1-g:3,4-g']diquinoline-2,9-dicarboxylate (I) is accomplished by heating said diadduct (II) at a relatively high temperature. The neat diadduct (II) can be heated directly, but it is preferable to put it into a solvent that can function as a heat transfer medium. Any high boiling inert solvent such as a mineral oil, hexamethylphosphoric triamide, diphenyl ether, or Dowtherm A (a commercial mixture of diphenyl and diphenyl ether), is suitable. The ring cyclization step is preferably carried out at temperatures of from about 220°C. to about 280°C., although lower or higher temperatures can be employed, if desired. Particularly preferred solvents are Dowtherm A or diphenyl ether, which boil at about 250°C., thus enabling the ring cyclization to occur during reflux. (At this point of the process, different esters can be prepared at the R position of the carboxy group, e.g., by a standard transesterification reaction.)

An advantage of the elevated temperature during the ring cyclization step is that any adduct formed in the preceding step which is not in a position to cyclize, since it is trans to the benzene ring, is isomerized to the cis configuration during the heating, thereby allowing substantial yields of the desired compound to be produced. This trans adduct preparation occurs more frequently when an aprotic solvent and a dialkylacetylene dicarboxylate are used in the adduct formation step.

3. In the third step of the process, a 2,9-dicarboxylate ester (I) resulting from step (2) is converted to its corresponding 2,9-dicarboxylic acid (I) by treatment with a base (e.g., by heating the former with an aqueous solution of an alkali metal hydroxide such as sodium hydroxide or potassium hydroxide), then adding to the reaction mixture a strong acid (such as trifluoroacetic acid, sulfuric acid, nitric acid and the like) to give a solid 2,9-dicarboxylic acid (I) that can be collected, for example, by filtration. A thus produced dicarboxylic acid (I) can be readily converted to a corresponding amine salt or alkali metal derivative by contacting the former with two equivalents of the desired amine or al-

kali metal and heating in a sufficient amount of water to effect solubilization. The crystalline salts can be precipitated by the addition of methanol.

PROCESS B

The compounds of the formula

wherein A, R and Z have the same meaning as above, are prepared by the steps comprising

1. mixing, in the presence of an acid catalyst, a corresponding compound of the formula

wherein Q and Z have the same meaning as above, with a corresponding compound of the formula

wherein A has the same meaning as above, to yield a corresponding compound of the formula

wherein A, Q and Z have the same meaning as above;

2. heating a thus produced corresponding compound resulting from step (1) to yield a corresponding compound of Formula I, above

A third step is required for preparing the compounds of the formula

wherein A and Z have the same meaning as above, namely, hydrolyzing a corresponding compound produced in the manner described in step (2) immediately above and having the formula

wherein A, Q and Z have the same meaning as above, e.g., with an alkali metal hydroxide and then adding thereto a strong acid.

1. The first step of Process B comprises mixing an alkali metal salt of a di(alkyl or phenyl) oxalacylate (IV') with a 2,7-diaminofluorene (III), in a molar ratio of at least 2 of the former (IV') to 1 of the latter (III) reactants, in the presence of an acid catalyst, to yield a corresponding diadduct, a tetraalkyl 2,2'-[(9-oxofluorene-2,6-diyl)diimino] bis [3-alkyl(or phenyl) butenedioate] (II'). Molar ratios in excess of 2:1 (e.g., 3:1; to

5:1) are also satisfactory. When using the oxaloacylate reagent (IV') to form the diadduct, there should be a sufficient amount of acid present to protonate the oxaloacylate carbon and catalyze the removal of the keto grouping as water. The acid can also serve as a solvent for the two reagents as well. For example, glacial acetic acid, propionic acid, p-toluene sulfonic acid, and butyric acid are acids which can be used. If a further reagent is needed to place the two reactants into solution, (or a cosolvent desired), benzene, toluene, diethyl ether, dioxane, tetrahydrofuran, or alcohols from one to about four carbon atoms can be employed. The length of time for the formation of the diadduct is temperature dependent. At room temperature the reaction proceeds rather slowly, but as the temperature is raised, reaction time is decreased. Acceptable reaction times are achieved at temperatures ranging from about 40° to about 70°C., although reaction temperatures can be above 100°C. if desired.

2, 3. These steps of Process B are the same as the corresponding steps of Process A, above.

All of the compounds included within Formula I, above, and the intermediates therefor, can be isolated from their respective reaction mixtures by conventional means, for example, when a water-miscible solvent is used, by pouring the reaction mixture into water and separating the resulting precipitate by filtration or by extraction with water-immiscible solvents. Additional purification of the products can be accomplished by conventional means, for example, by elution chromatography from an adsorbent column with a suitable solvent such as acetone, ethyl acetate, ether, methylene chloride and Skellysolve B (hexanes), mixtures and combinations of these solvents; also by gradient elution chromatography from an adsorbent column with a suitable mixture of solvents, such as, methylene chloride-Skellysolve B, acetone-Skellysolve B, and the like.

The novel compounds (I) of this invention have antiallergic (especially anti-asthmatic) activity, inhibiting a positive Passive Cutaneous Anaphylactic (PCA) test induced by the rat immunochemical counterpart of human IgE (regain), and is considered indicative of inhibiting human allergic activity. This activity is apparent when these compounds are tested for their inhibition of the rat PCA reaction. The PCA assay is described by I. Mota in Immunology 5:11 (1962).

DETAILED DESCRIPTION

It is to be understood that this invention is not to be limited to the exact details of operation or exact compounds shown and described herein, as obvious modifications and equivalents will be apparent to one skilled in the art, and the invention is therefore to be limited only by the scope of the appended claims.

Preparation 1: 2,7-diaminofluoren-9-ethyl-9-ol (III)

To a suspension of 2,7-diaminofluoren-9-one (III) (prepared as in Ann. 390, 225) in 200 ml. of tetrahydrofuran, 32 ml. of a 3 M ether solution of ethyl magnesium bromide is carefully added. The reaction mixture is stirred at room temperature for about 1 hour and then heated at reflux for about 1 hour. The mixture is allowed to cool and then poured into a mixture of ice and ammonium chloride. The solid 2,7-diaminofluoren-9-ethyl-9-ol (III) is collected by filtration.

Following the procedure of Preparation 1 but substituting an equivalent amount of another Grignard reagent, such as

1. methyl magnesium bromide,
2. propyl magnesium bromide,
3. isopropyl magnesium fluoride,
4. butyl magnesium bromide,
5. isobutyl magnesium iodide,
6. sec. butyl magnesium bromide,
7. t. butyl magnesium chloride,
8. pentyl magnesium bromide,
9. isopentyl magnesium bromide,
10. t. pentyl magnesium chloride,
11. hexyl magnesium bromide, etc.,

15 yields, respectively,

1. 2,7-diaminofluoren-9-methyl-9-ol (III),
2. 2,7-diaminofluoren-9-propyl-9-ol (III),
3. 2,7-diaminofluoren-9-isopropyl-9-ol (III),
4. 2,7-diaminofluoren-9-butyl-9-ol (III),
5. 2,7-diaminofluoren-9-isobutyl-9-ol (III),
6. 2,7-diaminofluoren-9-sec. butyl-9-ol (III),
7. 2,7-diaminofluoren-9-t. butyl-9-ol (III),
8. 2,7-diaminofluoren-9-pentyl-9-ol (III),
9. 2,7-diaminofluoren-9-isopentyl-9-ol (III),
10. 2,7-diaminofluoren-9-t. pentyl-9-ol (III),
11. 2,7-diaminofluoren-9-hexyl-9-ol (III), etc.

Preparation 2 2,7-diamino-9-ethylidenefluoren (III)

In 250 ml. of benzene containing 0.1 g. of p-toluenesulfonic acid as catalyst, 2 g. of 2,7-diamino-9-ethyl-9-ol (III) (obtained as in Preparation 1, above) is heated at reflux with the constant removal of water. When the theoretical amount of water is collected, the reaction mixture is cooled. The reaction mixture is washed with about 100 ml. of saturated aqueous sodium bicarbonate solution and about 100 ml. of water. The organic layer is dried with anhydrous sodium sulfate and the solvent removed to give 2, 7-diamino-9-ethylidenefluoren (III).

Following the procedure of Preparation 2 but substituting another 2,7-diamino-9-alkyl-9-ol (III) for 2,7-diamino-9-ethyl-9-ol (III), such as

1. 2,7-diamino-9-propyl-9-ol (III),
2. 2,7-diamino-9-butyl-9-ol (III),
3. 2,7-diamino-9-isobutyl-9-ol (III),
4. 2,7-diamino-9-pentyl-9-ol (III),
5. 2,7-diamino-9-isopentyl-9-ol (III),
6. 2,7-diamino-9-hexyl-9-ol (III),
7. 2,7-diamino-9-isoheptyl-9-ol (III), etc.,

50 yields, respectively,

1. 2,7-diamino-9-propylidenefluoren (III),
2. 2,7-diamino-9-butylidenefluoren (III),
3. 2,7-diamino-9-isobutylidenefluoren (III),
4. 2,7-diamino-9-pentylidenefluoren (III),
5. 2,7-diamino-9-isopentylidenefluoren (III),
6. 2,7-diamino-9-hexylidenefluoren (III),
7. 2,7-diamino-9-isoheptylidenefluoren (III), etc.

Preparation 3 2,7-diamino-9-ethylfluoren (III)

A suspension of 2 g. of 2,7-diamino-9-ethylidenefluoren (III) (obtained as in Preparation 2, above) and 0.1 g. of 5% palladium on charcoal catalyst in 200 ml. of methanol is shaken under hydrogen at a pressure of 40 pounds/square inch until hydrogen uptake ceases. Removal of the catalyst and the solvent leaves 2,7-diaminofluoren (III).

Following the procedure of Preparation 3 but substituting another 2,7-diamino-9-alkylidenefluoren (III) for 2,7-diamino-9-ethylidenefluoren (III), such as

1. 2,7-diamino-9-propylidenefluorene (III),
2. 2,7-diamino-9-butylidenefluorene (III),
3. 2,7-diamino-9-isopentylidenefluorene (III),
4. 2,7-diamino-9-hexylidenefluorene (III), etc., yields, respectively,
1. 2,7-diamino-9-propylfluorene (III),
2. 2,7-diamino-9-butylfluorene (III),
3. 2,7-diamino-9-isopentylfluorene (III),
4. 2,7-diamino-9-hexylfluorene (III), etc.

Preparation 4 2,7-diamino-9-ethyl-9-methylfluorene (III)

An ether solution of 2 g. of 2,7-diamino-9-ethylfluorene (III) (obtained as in Preparation 3) is treated with an excess (1.6 ml. in hexane) of butyl lithium. Methyl iodide is added to the reaction mixture, which is stirred for about 1 hour and then poured into ice water. The resulting mixture is extracted with methylene chloride. The organic phase is dried over anhydrous sodium sulfate and the solvent removed to give 2,7-diamino-9-ethyl-9-methylfluorene (III).

Following the procedure of Preparation 4 but substituting another 2,7-diamino-9-alkylfluorene (III) for 2,7-diamino-9-ethylfluorene (III) and another alkyl iodide for methyl iodide, such as

1. 2,7-diamino-9-methylfluorene (III) and propyl iodide,
2. 2,7-diamino-9-butylfluorene (III) and methyl iodide,
3. 2,7-diamino-9-propylfluorene (III) and pentyl iodide,
4. 2,7-diamino-9-pentylfluorene (III) and butyl iodide,
5. 2,7-diamino-9-isohexylfluorene (III and isobutyl iodide, etc., yields, respectively,
1. 2,7-diamino-9-methyl-9-propylfluorene (III),
2. 2,7-diamino-9-butyl-9-methylfluorene (III),
3. 2,7-diamino-9-pentyl-9-propylfluorene (III),
4. 2,7-diamino-9-butyl-9-pentylfluorene (III),
5. 2,7-diamino-9-isobutyl-9-isohexylfluorene (III), etc.

EXAMPLE 1:

1,4,7,10-tetrahydro-4,7,12-trioxo-12H-cyclopenta[2,1-g:3,4-g']diquinoline-2,9-dicarboxylic acid (I)

PART A: Tetramethyl 2,2'-(9-oxofluorene-2,7-diyl)diimino]dibutenedioate (II)

7 g. of dimethylacetylene dicarboxylate (IV) (prepared as in Org. Synthesis 32, 55) is added slowly to a mixture of 5 g. of 2,7-diaminofluoren-9-one (III) (prepared as in Ann. 390, 225) and 100 ml. of methanol. The reaction mixture is stirred at room temperature for about 72 hours. The resulting solid is collected by filtration and recrystallized from acetone to give 7 g. of reddish-brown needles of tetramethyl 2,2'-(9-oxofluorene-2,7-diyl)diimino]dibutenedioate (II) melting between 158° to 161° C.

Anal. Calcd. for: C₂₅H₂₂O₉N₂: C, 60.73; H, 4.49; N, 5.67. Found: C, 60.37; H, 4.58; N, 5.60.

PART B: Dimethyl

1,4,7,10-tetrahydro-4,7,12-trioxo-12H-cyclopenta[2,1-g:3,4-g']diquinoline-2,9-dicarboxylate (I)

2 g. of the compound (II) obtained in Part A, above, is carefully added to 100 ml. of Dowtherm A refluxing

at about 250°C. The reaction mixture is refluxed for about 5 minutes, then allowed to cool to room temperature. The resulting solid is collected by filtration and washed well with acetone; it weighs 1.4 g. and melts above 310°C. The low solubility of this compound in common organic solvents precludes meaningful elemental analysis. Its infrared absorption spectrum (Nujol) is consistent with the expected product, dimethyl 1,4,7,10-tetrahydro-4,7,12-trioxo-12H-cyclopenta[2,1-g:3,4-g']diquinoline-2,9-dicarboxylate (I).

PART C: Disodium

1,4,7,10-tetrahydro-4,7,12-trioxo-12H-cyclopenta[2,1-g:3,4-g']diquinoline-2,9-dicarboxylate (I)

1 g. of the diester compound (I) obtained in Part B, above, is heated at reflux for about 1 hour in 10 ml. of 1 N aqueous sodium hydroxide solution. The reaction mixture is allowed to cool to room temperature to yield disodium 1,4,7,10-tetrahydro-4,7,12-trioxo-12H-cyclopenta[2,1-g:3,4-g']diquinoline-2,9-dicarboxylate (I).

PART D:

1,4,7,10-Tetrahydro-4,7,12-trioxo-12H-cyclopenta[2,1-g:3,4-g']diquinoline-2,9-dicarboxylic acid (I)

The cooled solution of the disodium compound (I) obtained in Part C, above, is acidified with concentrated hydrochloric acid to pH 3. The resulting solid is collected by filtration to give 1 g. of 1,4,7,10-tetrahydro-4,7,12-trioxo-12H-cyclopenta[2,1-g:3,4-g']diquinoline-2,9-dicarboxylic acid (I).

EXAMPLE 2:

1,4,7,10-Tetrahydro-4,7,12-trioxo-12H-cyclopenta[2,1-g:3,4-g']diquinoline-2,9-dicarboxylic acid (I)

Following the procedure of Example 1 but substituting diethylacetylene dicarboxylate (IV) [prepared as in J. Chem. Soc. 678 (1948)] for dimethylacetylene dicarboxylate in Part A thereof, yields tetraethyl 2,2'-(9-oxofluorene-2,7-diyl)diimino]di-butenedioate (II), diethyl 1,4,7,10-tetrahydro-4,7,12-trioxo-12H-cyclopenta[2,1-g:3,4-g']diquinoline-2,9-dicarboxylate (I), disodium 1,4,7,10-tetrahydro-4,7,12-trioxo-12H-cyclopenta[2,1-g:3,4-g']diquinoline-2,9-dicarboxylate (I) and 1,4,7,10-tetrahydro-4,7,12-trioxo-12H-cyclopenta[2,1-g:3,4-g']diquinoline-2,9-dicarboxylic acid (I).

EXAMPLE 3:

1,4,7,10-Tetrahydro-4,7,12-trioxo-12H-cyclopenta[2,1-g:3,4-g']diquinoline-2,9-dicarboxylic acid (I)

Following the procedure of Example 1 but substituting dipropylacetylene dicarboxylate (IV) [prepared as in J. Chem. Soc. 678 (1948)] as one of the starting materials in Part A thereof, and potassium hydroxide for sodium hydroxide in Part C thereof, yields tetrapropyl 2,2'-(9-oxofluorene-2,7-diyl)diimino]di-butenedioate (II), dipropyl 1,4,7,10-tetrahydro-4,7,12-trioxo-12H-cyclopenta[2,1-g:3,4-g']diquinoline-2,9-dicarboxylate (I), dipotassium 1,4,7,10-tetrahydro-4,7,12-trioxo-12H-cyclopenta[2,1-g:3,4-g']diquinoline-2,9-dicarboxylate (I) and 1,4,7,10-tetrahydro-4,7,12-trioxo-12H-cyclopenta[2,1-g:3,4-g']diquinoline-2,9-dicarboxylic acid (I).

EXAMPLE 4:

1,4,7,10-Tetrahydro-4,7-dioxo-12H-cyclopenta[2,1-g:3,4-g']diquinoline-2,9-dicarboxylic acid (I)

Following the procedure of Example 1 but substituting 2,7-diaminofluorene (III) (prepared as in Ber. 64, 1793) in Part A thereof, yields tetramethyl 2,2'-(fluorene-2,7-diyl)diimino]di-butendioate (II), dimethyl 1,4,7,10-tetrahydro-4,7-dioxo-12H-cyclopenta[2,1-g:3,4-g']diquinoline-2,9-dicarboxylate (I), disodium 1,4,7,10-tetrahydro-4,7-dioxo-12H-cyclopenta[2,1-g:3,4-g']diquinoline-2,9-dicarboxylate (I) and 1,4,7,10-tetrahydro-4,7-dioxo-12H-cyclopenta[2,1-g:3,4-g']diquinoline-2,9-dicarboxylic acid (I).

EXAMPLE 5:

1,4,7,10-Tetrahydro-4,7-dioxo-12-ol-12H-cyclopenta[2,1-g:3,4-g']diquinoline-2,9-dicarboxylic acid (I)

Following the procedure of Example 1 but substituting diisopropylacetylene dicarboxylate (IV) [prepared as in J. Chem. Soc. 678 (1948)] and 2,7-diaminofluorene-9-ol (III) (prepared as in Ann. Chim. 14, 5) as starting materials in Part A thereof, yields tetraisopropyl 2,2'-(fluorene-9-ol-2,7-diyl)dimino]dibutendioate (II), diisopropyl 1,4,7,10-tetrahydro-4,7-dioxo-12-ol-12H-cyclopenta[2,1-g:3,4-g']diquinoline-2,9-dicarboxylate (I), disodium 1,4,7,10-tetrahydro-4,7-dioxo-12-ol-12H-cyclopenta[2,1-g:3,4-g']diquinoline-2,9-dicarboxylate (I) and 1,4,7,10-tetrahydro-4,7-dioxo-12-ol-12H-cyclopenta[2,1-g:3,4-g']diquinoline-2,9-dicarboxylic acid (I).

EXAMPLE 6:

1,4,7,10-Tetrahydro-4,7-dioxo-12-methyl-12-ol-12H-cyclopenta[2,1-g:3,4-g']diquinoline-2,9-dicarboxylic acid (I)

Following the procedure of Example 1 but substituting dibutylacetylene dicarboxylate (IV) [prepared as in J. Chem. Soc. 678 (1948)] and 2,7-diaminofluorene-9-methyl-9-ol (III) (prepared as in Preparation 1, above) as starting materials in Part A thereof, yields tetrabutyl 2,2'-(fluorene-9-methyl-9-ol-2,7-diyl)diimino]dibutendioate (II), dibutyl 1,4,7,10-tetrahydro-4,7-dioxo-12-methyl-12-ol-12H-cyclopenta[2,1-g:3,4-g']diquinoline-2,9-dicarboxylate (I), disodium 1,4,7,10-tetrahydro-4,7-dioxo-12-methyl-12-ol-12H-cyclopenta[2,1-g:3,4-g']diquinoline-2,9-dicarboxylate (I) and 1,4,7,10-tetrahydro-4,7-dioxo-12-methyl-12-ol-12H-cyclopenta[2,1-g:3,4-g']diquinoline-2,9-dicarboxylic acid (I).

EXAMPLE 7:

1,4,7,10-Tetrahydro-4,7-dioxo-12-ethyl-12-ol-12H-cyclopenta[2,1-g:3,4-g']diquinoline-2,9-dicarboxylic acid (I)

Following the procedure of Example 1 but substituting 2,7-diaminofluorene-9-ethyl-9-ol (III) (obtained as in Preparation 1, above) for 2,7-diaminofluorene-9-one (III) in Part A thereof, yields 1,4,7,10-tetrahydro-4,7-dioxo-12-ethyl-12-ol-12H-cyclopenta[2,1-g:3,4-g']diquinoline-2,9-dicarboxylic acid (I).

Following the procedure of Example 7 but substituting 2,7-diaminofluorene-9-isopropyl-9-ol (III), yields 1,4,7,10-tetrahydro-4,7-dioxo-12-isopropyl-12-ol-12H-

cyclopenta[2,1-g:3,4-g']diquinoline-2,9-dicarboxylic acid (I).

EXAMPLE 8:

1,4,7,10-Tetrahydro-4,7-dioxo-12-ethylidene-12H-cyclopenta[2,1-g:3,4-g']diquinoline-2,9-dicarboxylic acid (I)

Following the procedure of Example 1 but substituting 2,7-diamino-9-ethylidenefluorene (III) (obtained as in Preparation 2, above) for 2,7-diaminofluorene-9-one (III) in Part A thereof, yields 1,4,7,10-tetrahydro-4,7-dioxo-12-ethylidene-12H-cyclopenta[2,1-g:3,4-g']diquinoline-2,9-dicarboxylic acid (I).

Following the procedure of Example 8 but substituting 2,7-diamino-9-propylidenefluorene (III), yields 1,4,7,10-tetrahydro-4,7-dioxo-12-propylidene-12H-cyclopenta[2,1-g:3,4-g']diquinoline-2,9-dicarboxylic acid (I).

EXAMPLE 9:

1,4,7,10-Tetrahydro-4,7-dioxo-12-ethyl-12H-cyclopenta[2,1-g:3,4-g']diquinoline-2,9-dicarboxylic acid (I)

Following the procedure of Example 1 but substituting 2,7-diamino-9-ethylfluorene (III) (obtained as in Preparation 3, above) for 2,7-diaminofluorene-9-one (III) in Part A thereof, yields 1,4,7,10-tetrahydro-4,7-dioxo-12-ethyl-12H-cyclopenta[2,1-g:3,4-g']diquinoline-2,9-dicarboxylic acid (I).

Following the procedure of Example 9 but substituting 2,7-diamino-9-isopropylfluorene (III), yields 1,4,7,10-tetrahydro-4,7-dioxo-12-isopropyl-12H-cyclopenta[2,1-g:3,4-g']diquinoline-2,9-dicarboxylic acid (I).

EXAMPLE 10:

1,4,7,10-Tetrahydro-4,7-dioxo-12-ethyl-12-methyl-12H-cyclopenta[2,1-g:3,4-g']diquinoline-2,9-dicarboxylic acid (I)

Following the procedure of Example 1 but substituting 2,7-diamino-9-ethyl-9-methylfluorene (III) (obtained as in Preparation 4, above) for 2,7-diaminofluorene-9-one (III) in Part A thereof, yields 1,4,7,10-tetrahydro-4,7-dioxo-12-ethyl-12-methyl-12H-cyclopenta[2,1-g:3,4-g']diquinoline-2,9-dicarboxylic acid (I).

Following the procedure of Example 10 but substituting 2,7-diamino-9-methyl-9-propylfluorene (III), yields 1,4,7,10-tetrahydro-4,7-dioxo-12-methyl-12-propyl-12H-cyclopenta[2,1-g:3,4-g']diquinoline-2,9-dicarboxylic acid (I).

EXAMPLE 11:

Di(tris-hydroxymethyl)methylammonium
1,4,7,10-tetrahydro-4,7,12-trioxo-12H-cyclopenta[2,1-g:3,4-g']diquinoline-2,9-dicarboxylic acid (I)

To 10 ml of water, 1 g. of 1,4,7,10-tetrahydro-4,7,12-trioxo-12H-cyclopenta[2,1-g:3,4-g']diquinoline-2,9-dicarboxylic acid (I) (prepared as in Example 1) is added. To this, 0.77 g. of tris-hydroxymethyl)aminomethane is added. The mixture is heated for several minutes until solution is complete. The crystalline di(tris-hydroxymethyl)methylammonium 1,4,7,10-tetrahydro-4,7,12-trioxo-12H-cyclopenta[2,1-g:3,4-g']diquinoline-2,9-dicarboxylic acid (I) is precipitated by the addition of methanol to the mixture.

Following the procedure of Example 11 but substituting another starting material for 1,4,7,10-tetrahydro-4,7,12-trioxo-12H-cyclopenta[2,1-g:3,4-g']diquinoline-2,9-dicarboxylic acid (I), such as

1. 1,4,7,10-tetrahydro-4,7-dioxo-12H-cyclopenta[2,1-g:3,4-g']diquinoline-2,9-dicarboxylic acid (I),
2. 1,4,7,10-tetrahydro-4,7-dioxo-12-ol-12H-cyclopenta[2,1-g:3,4-g']diquinoline-2,9-dicarboxylic acid (I),
3. 1,4,7,10-tetrahydro-4,7-dioxo-12-methyl-12-ol-12H-cyclopenta[2,1-g:3,4-g']diquinoline-2,9-dicarboxylic acid (I),
4. 1,4,7,10-tetrahydro-4,7-dioxo-12-ethylidene-12H-cyclopenta[2,1-g:3,4-g']diquinoline-2,9-dicarboxylic acid (I),
5. 1,4,7,10-tetrahydro-4,7-dioxo-12-methyl-12-propyl-12H-cyclopenta[2,1-g:3,4-g']diquinoline-2,9-dicarboxylic acid (I), etc.,

yields, respectively,

1. di(tris-hydroxymethyl)methylammonium 1,4,7,1-0-tetrahydro-4,7-dioxo-12H-cyclopenta[2,1-g:3,4-g']diquinoline-2,9-dicarboxylic acid (I),
2. di(tris-hydroxymethyl)methylammonium 1,4,7,1-0-tetrahydro-4,7-dioxo-12-ol-12H-cyclopenta[2,1-g:3,4-g']diquinoline-2,9-dicarboxylic acid (I),
3. di(tris-hydroxymethyl)methylammonium 1,4,7,1-0-tetrahydro-4,7-dioxo-12-methyl-12-ol-12H-cyclopenta[2,1-g:3,4-g']diquinoline-2,9-dicarboxylic acid (I),
4. di(tris-hydroxymethyl)methylammonium 1,4,7,1-0-tetrahydro-4,7-dioxo-12-ethylidene-12H-cyclopenta[2,1-g:3,4-g']diquinoline-2,9-dicarboxylic acid (I).
5. di(tris-hydroxymethyl)methylammonium 1,4,7,1-0-tetrahydro-4,7-dioxo-12-methyl-12-propyl-12H-cyclopenta[2,1-g:3,4-g']diquinoline-2,9-dicarboxylic acid (I), etc.

Following the procedures of the immediately preceding paragraph and of Example 11, but substituting for tris(hydroxy-methyl)aminomethane (in an appropriate solvent in accordance with the art, when necessary or desirable), an amine such as methylamine, dimethylamine, trimethylamine, ethylamine, diethylamine, triethylamine, propylamine, dipropylamine, tripropylamine, isopropylamine, diisopropylamine, triisopropylamine, ethanolamine, D-threo-2-amino-1-(p-nitrophenyl)-1,3-propanediol, N,N-bis(hydroxyethyl)-piperazine, 2-amino-2-methyl-1-propanol, 2-amino-2-methyl-1,3-propanediol or 2,2-bis(hydroxymethyl)-2,2',2"-nitrilotriethanol, yields the corresponding di(substituted ammonium) salt of a 1,4,7,10-tetrahydro-4,7-dioxo (4,7,12-trioxo, 4,7-dioxo-12-ol, 4,7-dioxo-12-alkyl, -12-ol, 4,7-dioxo-12-alkylidene, or 4,7-dioxo-12-lakylidene, or 4,7-dioxo-12-dialkyl) -12H-cyclopenta[2,1-g:3,4-g']diquinoline-2,9-dicarboxylic acid (I).

The compositions of the present invention are presented for administration to humans and animals in unit dosage forms, such as tablets, capsules, pills, suppositories, powders, granules, sterile parenteral solutions or suspensions, and oral solutions or suspensions, and oil-in-water and water-in-oil emulsions containing suitable quantities of the compound of Formula Ia. The preferred method of administration is by inhalation into the lung by means of an aerosol or powder for insufflation.

For oral administration either solid or fluid unit dosage forms can be prepared. For preparing solid compositions such as tablets, the compound of Formula Ia is mixed with conventional ingredients such as talc, magnesium stearate, dicalcium phosphate, magnesium aluminum silicate, calcium sulfate, starch, lactose, acacia, methylcellulose, and functionally similar materials as pharmaceutical diluents or carriers. Capsules are prepared by mixing the compound with an inert pharmaceutical diluent and filling the mixture into a hard gelatin capsule of appropriate size. Soft gelatin capsules are prepared by machine encapsulation of a slurry of the compound with an acceptable vegetable oil, light liquid petrolatum or other inert oil.

Fluid unit dosage forms for oral administration such as syrups, elixirs, and suspensions can be prepared. The water-soluble forms can be dissolved in an aqueous vehicle together with sugar, aromatic flavoring agents and preservatives to form a syrup. An elixir is prepared by using a hydro-alcoholic (ethanol) vehicle with suitable sweeteners such as sugar and saccharin, together with an aromatic flavoring agent.

Suspensions can be prepared with a syrup vehicle with the aid of a suspending agent such as acacia, tragacanth, methylcellulose and the like.

For parenteral administration, fluid unit dosage forms are prepared utilizing the compound and a sterile vehicle, water being preferred. The compound, depending on the vehicle and concentration used, can be either suspended or dissolved in the vehicle. In preparing solutions the compound can be dissolved in water for injection and filter sterilized before filling into a suitable vial or ampul and sealing. Advantageously, adjuvants such as a local anesthetic, preservative and buffering agents can be dissolved in the vehicle. To enhance the stability, the composition can be frozen after filling into the vial and the water removed under vacuum. The dry lyophilized powder is then sealed in the vial and an accompanying vial of water for injection is supplied to reconstitute the liquid prior to use. Parenteral suspensions are prepared in substantially the same manner except that the compound is suspended in the vehicle instead of being dissolved and sterilization cannot be accomplished by filtration. The compound can be sterilized by exposure to ethylene oxide before suspending in the sterile vehicle. Advantageously, a surfactant or wetting agent is included in the composition to facilitate uniform distribution of the compound.

The preferred compositions are those adapted for inhalation into the lung and containing a water soluble form of a compound of the Formula Ia.

Compositions for inhalation are of three basic types: (1) a powder mixture preferably micro-pulverized; (2) an aqueous solution to be sprayed with a nebulizer; (3) an aerosol with volatile propellant in a pressurized container.

The powders are quite simply prepared by mixing a compound of the formula with a solid base which is compatible with lung tissue, preferably lactose. The powders are packaged in a device adapted to emit a measured amount of powder when inhaled through the mouth.

Aqueous solutions are prepared by dissolving the compound of the Formula Ia in water and adding salt to provide an isotonic solution and buffering to a pH compatible with inhalation. The solutions are dispersed

in a spray device or nebulizer and sprayed into the mouth while inhaling.

Aerosols are prepared by dissolving a compound of the Formula I in water or ethanol and mixing with a volatile propellant and placing in a pressurized container having a metering valve to release a predetermined amount of material.

The liquefied propellant employed is one which has a boiling point below 65°F. at atmospheric pressure. For use in compositions intended to produce aerosols for medicinal use, the liquefied propellant should be non-toxic. Among the suitable liquefied propellants which may be employed are the lower alkanes containing up to five carbon atoms, such as butane and pentane, or a lower alkyl chloride, such as methyl, ethyl, or propyl chlorides. The most suitable liquefied propellants are the fluorinated and fluorochlorinated lower alkanes such as are sold under the trademarks "Freon" and "Genetron". Mixtures of the above-mentioned propellants may suitably be employed. Examples of these propellants are dichlorodifluoromethane ("Freon 12"), dichlorotetrafluoroethane ("Freon 114"), trichloromonofluoromethane ("Freon 11"), dichloromonofluormethane ("Freon 21"), monochlorodifluormethane ("Freon 22"), trichlorotrifluoroethane ("Freon 113"), difluoroethane ("Genetron 142-A") and monochlorotrifluoromethane ("Freon 13").

The term, "unit dosage form", as used in the specification and claims, refers to physically discrete units suitable as unitary dosages for human subjects and animals, each unit containing a predetermined quantity of active material calculated to produce the desired therapeutic effect in association with the required pharmaceutical diluent, carrier or vehicle. The specifications for the novel unit dosage forms of this invention are dictated by and directly dependent on (a) the unique characteristics of the active material and the particular effect to be achieved and (b) the limitations inherent in the art of compounding such an active material for use in humans an animals, as disclosed in detail in this specification, these being features of the present invention. Examples of suitable unit dosage forms in accord with this invention are tablets, capsules, pills, suppositories, powder packets, granules, wafers, cachets, teaspoonfuls, tablespoonfuls, dropperfuls, ampuls, vials, aerosols with metered discharges, segregated multiples of any of the foregoing, and other forms as herein described.

The dosage of the compound for treatment depends on the route of administration and the potency of the specific compound. For a single dose administered parenterally or by inhalation, a dosage schedule of from about 0.01 to 50 mg. embraces the effective range for preventing allergic attack for which the compositions are effective. The dosage to be administered can be repeated up to 4 times daily. However, when it is necessary to repeat treatment, a preferred dosage schedule reduces the secondary treatment dosage to from about 0.5% to about 20% of the above dosages, more specifically, from about 1 to about 20% of the above dosages. In this manner a state of allergy prophylaxis can be maintained. The reduced dosage is taken until that dosage no longer provides effective protection. At that time the larger dosage is repeated, followed by the reduced dosage. An example of such a dosage schedule is the following: An asthmatic insufflates 0.5 mg. of 1,4-

,7,10-tetrahydro-4,7,12-trioxo-12H-cyclopenta[2,1-g:3,4-g']diquinoline-2,9-dicarboxylic acid (I). After a time span of four hours the asthmatic insufflates 0.05 mg. of the same compound and every four to six hours thereafter insufflates 0.05 mg. of the same compound until effective asthma prophylaxis is not provided. The asthmatic individual then insufflates 0.5 mg. of the same compound, then reduces the insufflation dosage to 0.05 mg. four to six hours later. The dosage schedule continues in this manner. The oral dose is from about 0.1 to about 500 mg. in a single dose.

The administration of the compositions of the present invention to humans an animals provides a method for the prophylactic treatment of allergy or all anaphylactic reactions of a reagin or non-reagin mediated nature. That is to say, these compositions when administered to a sensitized individual prior to the time that the individual comes into contact with substances (antigens), to which he is allergic, will prevent the allergic reaction which would otherwise occur.

For example, the process can be used for prophylactic treatment of such chronic conditions as bronchial asthma, allergic conjunctivitis, allergic rhinitis, food allergy, hay fever, urticaria, and auto-immune diseases.

EXAMPLE 12

A lot of 10,000 tablets, each containing 0.1 mg. of 1,4,7,10-tetrahydro-4,7,12-trioxo-12H-cyclopenta[2,1-g:3,4-g']diquinoline-2,9-dicarboxylic acid (I) is prepared from the following types and amounts of ingredients:

35	1,4,7,10-tetrahydro-4,7,12-trioxo-12H-cyclopenta[2,1-g:3,4-g']diquinoline-2,9-dicarboxylic acid (I)	1 Gm.
	Dicalcium phosphate	1,500 Gm.
	Methylcellulose, U.S.P. (15 cps.)	60 Gm.
40	Talc	150 Gm.
	Corn Starch	200 Gm.
	Calcium stearate	12 Gm.

The compound and dicalcium phosphate are mixed well, granulated with 7.5 percent solution of methylcellulose in water, passed through a No. 8 screen and dried carefully. The dried granules are passed through a No. 12 screen, mixed thoroughly with the talc, starch and magnesium stearate, and compressed into tablets.

These tablets are useful in preventing hay fever attacks at a dose of 1 tablet every four hours.

EXAMPLE 13

One thousand two-piece hard gelatin capsules, each containing 100 mg. of 1,4,7,10-tetrahydro-4,7,12-trioxo-12H-cyclopenta[2,1-g:3,4-g']diquinoline-2,9-dicarboxylic acid (I) are prepared from the following types and amounts of ingredients:

60	1,4,7,10-tetrahydro-4,7,12-trioxo-12H-cyclopenta[2,1-g:3,4-g']diquinoline-2,9-dicarboxylic acid (I), micronized	100 Gm.
	Talc	100 Gm.
65	Magnesium stearate	10 Gm.

The ingredients are mixed well and filled into capsules of the proper size.

2,9-dicarboxylate (I), disodium 1,4,7,10-tetrahydro-4,7-dioxo-12-ethylidene-12H-cyclopenta[2,1-g:3,4-g']diquinoline-2,9-dicarboxylate (I), 1,4,7,10-tetrahydro-4,7-dioxo-12-ethylidene-12H-cyclopenta[2,1-g:3,4-g']diquinoline-2,9-dicarboxylic acid (I), 1,4,7,10-tetrahydro-4,7-dioxo-12-ethyl-12H-cyclopenta[2,1-g:3,4-g']diquinoline-2,9-dicarboxylate acid (I), 1,4,7,10-tetrahydro-4,7-dioxo-12-ethyl-12-methyl-12H-cyclopenta[2,1-g:3,4-g']diquinoline-2,9-dicarboxylic acid (I), 1,4,7,10-tetrahydro-4,7-dioxo-12-methyl-12-propyl-12H-cyclopenta[2,1-g:3,4-g']diquinoline-2,9-dicarboxylic acid (I), di(tris-hydroxymethyl)-methyl ammonium 1,4,7,10-tetrahydro-4,7,12-trioxo-12H-cyclopenta[2,1-g:3,4-g']diquinoline-2,9-dicarboxylic acid (I), di(tris-hydroxymethyl)methylammonium 1,4,7,10-tetrahydro-4,7-dioxo-12H-cyclopenta[2,1-g:3,4-g']diquinoline-2,9-dicarboxylic acid (I), di(tris-hydroxymethyl)methylammonium 1,4,7,10-tetrahydro-4,7-dioxo-12-ol-12H-cyclopenta[2,1-g:3,4-g']diquinoline-2,9-dicarboxylic acid (I), di(tris-hydroxymethyl)methylammonium 1,4,7,10-tetrahydro-4,7-dioxo-12-methyl-12-ol-12H-cyclopenta[2,1-g:3,4-g']diquinoline-2,9-dicarboxylic acid (I), dimethylammonium 1,4,7,10-tetrahydro-4,7,12-trioxo-12H-cyclopenta[2,1-g:3,4-g']diquinoline-2,9-dicarboxylic acid (I), di(triethylammonium) 1,4,7,10-tetrahydro-4,7-dioxo-12-methyl-12-ol-12H-cyclopenta[2,1-g:3,4-g']diquinoline-2,9-dicarboxylic acid (I), di[D-threo-2-amino-1-(p-nitrophenyl)-1,3-propanediol] ammonium 1,4,7,10-tetrahydro-4,7-dioxo-12H-cyclopenta[2,1-g:3,4-g']diquinoline-2,9-dicarboxylic acid (I), etc.

We claim:

1. A compound of the formula

wherein R is selected from the group consisting of hydrogen, lower alkyl of 1 through 3 carbon atoms, an alkali metal, aluminum, calcium, magnesium, or an amine cation, said amine being selected from the group consisting of ammonia, an alkyl amine, ethanolamine, tris-hydroxymethylaminomethane, D-threo-2-amino-1-(p-nitrophenyl)-1,3-propanediol, 2-amino-2-methyl-1-propanol, 2-amino-2-methyl-1,3-propanediol and 2,2-bis(hydroxymethyl)-2,2',2"-nitrilotriethanol; Z is selected from the group consisting of hydrogen, and lower alkyl of 1 through 3 carbon atoms; A is selected from the group consisting of

wherein R¹ and R² are selected from the group consisting of hydrogen and lower alkyl of 1 through 6 carbon atoms.

20 2. A compound of claim 1 wherein R and Z are hydrogen and A is

namely, 1,4,7,10-tetrahydro-4,7,12-trioxo-12H-cyclopenta[2,1-g:3,4-g']diquinoline-2,9-dicarboxylic acid.

25 3. A compound of claim 1 wherein R is the cation of tris(hydroxymethyl)-aminomethane and Z is hydrogen and A is

namely, di(tris-(hydroxymethyl))methylammonium 1,4,7,10-tetrahydro-4,7,12-trioxo-12H-cyclopenta[2,1-g:3,4-g']diquinoline-2,9-dicarboxylate.
